United States Patent

Des. 237,679
Patented Nov. 18, 1975

237,679

DISPOSABLE FOOD TRAY

Harry A. Backus, 370 Neeb Road,
Cincinnati, Ohio 45238

Filed July 26, 1974, Ser. No. 492,218

Term of patent 14 years

Int. Cl. D7—99

U.S. Cl. D7—38

FIG. 1 is a top plan view showing my new design for a disposable food tray.

FIG. 2 is a bottom plan view.

FIG. 3 is a side elevational view.

FIG. 4 is an enlarged section taken on line 4—4 of FIG. 1.

I claim:

The ornamental design for a disposable food tray, as shown.
